UNITED STATES PATENT OFFICE.

EDGAR L. GOLD, OF BROOKLYN, NEW YORK, ASSIGNOR OF ONE-FOURTH TO CHARLES BEITEL AND ONE-FOURTH TO ALLEN LEOPOLD, BOTH OF BROOKLYN, NEW YORK, AND ONE-FOURTH TO JOHN J. EECHEET, OF WOODHAVEN, NEW YORK.

STOP MECHANISM.

1,188,926.

Specification of Letters Patent. Patented June 27, 1916.

Application filed August 12, 1915. Serial No. 45,178.

To all whom it may concern:

Be it known that I, EDGAR L. GOLD, a citizen of the United States, residing at Brooklyn, in the county of Kings and State 5 of New York, have invented certain new and useful Improvements in Stop Mechanism; and I do declare the following to be a full, clear, and exact description of the invention, such as will enable others skilled 10 in the art to which it appertains to make and use the same.

My invention relates to useful improvements in stop mechanisms for knitting machines and the like and has for its object to 15 improve upon the general construction of devices of this character to such an extent as to provide extremely simple and comparatively inexpensive construction, which, although possessing these characteristics, 20 will be highly efficient and durable.

With this general object in view, the invention resides in certain novel features of construction and in unique combinations of parts to be hereinafter fully described and 25 claimed, the descriptive matter being augmented by reference to the accompanying drawings wherein:

Figure 1 is a rear elevation of a portion of a knitting machine showing the application 30 of the invention to use, the several parts of such invention being so disposed as to allow the machine to operate; Fig. 2 is a view similar to Fig. 1 but illustrating the positions of parts when the stop mechanism 35 comes into operation; Fig. 3 is a detail vertical transverse section as viewed on the plane indicated by the line 3—3 of Fig. 1, showing more particularly the normal position of the circuit closer to be described; Fig. 4 is a view similar to Fig. 3 but illustrating the position of parts upon breakage 40 of the yarn or thread; Fig. 5 is yet another view similar to Fig. 3 and showing the manner in which the circuit closer operates 45 when excessive strain is placed upon the yarn; Fig. 6 is a horizontal section as viewed on the plane designated by the line 6—6 of Fig. 3; Fig. 7 is a perspective view of the circuit closing mechanism; Fig. 8 is 50 an additional perspective view disclosing the construction of the shaft shifting mem-

ber to be described; Fig. 9 is a detail vertical transverse section as seen along the plane designated by the line 9—9 of Fig. 1, but showing more particularly the brake mechanism; Figs. 10 and 11 are horizontal sections as seen on the plane of the line 10—10 of Fig. 9 showing different positions of parts; Fig. 12 is a diagram showing a portion of another type of knitting machine to 60 which the invention may be applied.

In referring to the accompanying drawings, similar reference characters will be used to designate corresponding parts throughout the several views, F indicating 65 the frame of a common type of knitting machine known to the art as the "American full fashioned knitting machine." This machine includes a power driven shaft S which may be rotated either by the electric motor 70 M as disclosed in Figs. 1 and 2, or by the belt B running normally upon the tight pulley P, but shiftable to a loose pulley P' (see Fig. 12).

If the motor M be provided, the switch 75 S' or the equivalent thereof is employed for breaking the circuit of the motor when desired, said switch being shown in the present applications as provided with an operating arm A which is secured by a set screw 80 or the like to the longitudinally shiftable control shaft C of the machine. If, on the other hand, the belt B be employed, a belt shifter A' may well be secured to the shaft C whereby when the latter is shifted in the 85 proper direction, the belt will be moved from the fixed pulley P to the loose pulley P', thus checking rotation of the shaft S under power, it being evident that the same final result is obtainable by shifting of the 90 switch S' by proper manipulation of the shaft C, if such switch be employed.

The construction of the parts so far briefly described forms no part of the present invention, but is disclosed merely for 95 the purpose of showing the coaction between such parts and the improved features which are designed to shift the shaft C in such a direction as to discontinue rotation of the shaft S under power, upon predetermined occurrences, such for instance as the prevalence of excessive strain upon the yarn

or thread or the breakage of such thread. To this end, the construction now to be described is provided.

Having an opening through which the controlling shaft C is normally free to slide, is a shaft shifting member 1 having a nose or the like 2 which is normally engaged by a pivoted catch 3 whereby to retain a coil spring 4 under tension, said spring being interposed between one end of the member 1 and one of the usual fixed bearings of the shaft C. By means yet to be described, the catch 3 is retracted upon predetermined occurrences, whereby to allow the spring 4 to forcibly project the member 1 into contact with a stop collar or the like 5 secured to the shaft C, thus shifting said shaft from the position seen in Fig. 1 to that disclosed in Fig. 2. This shifting of the shaft either opens the switch S' to break the circuit of the motor M or moves the belt shifter A' to shift the belt B from the fixed to the loose pulley, according to the design of the machine. In either case, however, the result is that rotation of the shaft S under power is checked. Needless to say, however, the shaft S will not cease to rotate immediately upon releasing of the driving means thereof, it being therefore highly expedient to provide an effective speed arresting brake applied to use simultaneously with the shifting of the shaft C by the spring 4. For this purpose, practically any preferred type of brake may be provided, but the post 6 preferably rises from the base of the machine and carries a fork 7 which is spaced a considerable distance from the shaft S, said fork supporting therein a split brake ring 8, such ring preferably having slotted ears 9 which are loosely connected to the ends of the fork 7 as most clearly depicted in Fig. 9. The ends of the split brake ring 8 are shown in the present application as rising in parallelism and as connected at their upper ends by a coil spring 10, their intermediate portions being normally spaced by the toggle links 11 when disposed in the position illustrated in Fig. 10, the outer ends of said links being pivoted to the free ends 50 of the ring 8 while their inner ends are connected to a head 12 on one end of a longitudinally disposed rod 13, the latter being slidably mounted in a hanger 14 which depends from the shaft C and having its opposite end secured in any preferred manner to an arm 15 which is disclosed in the present application as depending from the tubular member 1 and as having a guide fork 16 which loosely embraces the shaft S, whereby to retain the arm 15 and the member 1 in proper relation to the remaining parts of the device, at all times.

By the construction just described, when the member 1 is so shifted as to either open the switch S' or shift the belt B onto the

loose pulley, as the case may be, the toggle links 11 will be moved from the position seen in Fig. 10 to that disclosed in Fig. 11, thereby contracting the split brake ring 8 around a brake pulley 8^a which is fast on the shaft S, the result being that not only is the tension of the spring 4 exerted to apply the brake forcibly, but the spring 10 now likewise comes into action, thereby quickly arresting rotation of the shaft S and thus discontinuing operation of the entire machine.

It may be desirable to so prevent operation of the machine for a number of reasons, but in the present embodiment of the invention, this only takes place either when the thread or yarn Y breaks or when excessive strain is placed thereon which might cause breakage, a uniquely constructed strain and breakage detector D being provided for so doing. This detector is so constructed as to allow the same to close the circuit of a pair of electro-magnets 17 when excessive strain on the yarn or breakage thereof occurs, the aforesaid magnets 17 being positioned adjacent the pivoted catch 3, whereby when said magnets are energized, they will immediately release said catch, whereupon the stop mechanism comes into action in the manner above set forth.

The detector above mentioned is shown in the present embodiment of the invention as supported upon a hanger 18 which depends from a rail 19 extending longitudinally throughout substantially the entire length of the knitting machine, such machine being considered as formed of a number of independent units as is common in machines of this class, in which instance a post 18 depends from the rail 19 adjacent each unit, each one of said posts carrying one of the detectors D. However, since the construction of all of these devices is the same, but one is shown in the accompanying drawings and will now be described.

Positioned in rear of the hanger 18, and having a forwardly extending ear 20^a pivoted to the lower end thereof, is a horizontally disposed oscillatory bar 20 from one side of which a plurality of parallel fingers 21 project horizontally, while from the opposite side of said bar, a weighted arm 22 extends laterally. The opposite ends of the bar 20 are shown in the present embodiment of the invention as provided with upstanding ears 23 between which an additional horizontally positioned oscillatory bar 24 is pivoted, one side of said bar being equipped with a plurality of outstanding right-angular fingers 25 which are intermeshed with the fingers 21 as clearly disclosed in Figs. 6 and 7, while projecting from the opposite side of said bar 24, is an additional weighted arm 26 which is spaced above and to one side of the arm 22. 130

Under normal working of the machine, the yarn Y is passed beneath the fingers 21 and over the fingers 25, whereby a reliable tension is placed on said yarn and whereby the two arms 22 and 26 are held normally spaced equidistantly from a contact 27 which projects therebetween, (see more particularly Figs. 3 and 7). When, however, breakage of the yarn occurs, the uppermost weighted arm 26 is allowed to descend onto the contact 27, thus completing the circuit of the magnets 17 (see Fig. 4) through appropriate wiring yet to be described. On the other hand, when excessive strain is placed upon the yarn, the entire detector is rocked to the position disclosed in Fig. 5, whereupon the lowermost weighted arm 22 is presented to the contact 27 thus likewise completing the circuit of the magnets 17. Regardless of the manner in which this circuit be completed, the result is releasing of the catch 3, projection of the member 1 to discontinue rotation of the shaft S, under power, and the immediate application of the brake mechanism to prevent further rotation of said shaft S. By this manner of operation, imperfections in the weave as well as entanglements of the yarn or thread are prevented, as will be readily understood to those skilled in the art to which the invention relates, without requiring a more extended explanation.

As illustrative of one simple manner of providing an electric circuit to be completed by the detector D, the drawings illustrate in diagram, an electric battery 30 from one pole of which one wire 31 leads to one terminal of the magnets 17, while from the other pole of said battery a wire 33 extends to the pivot of the ear 20^a, this ear as well as all parts of the detector with the exception of the post 18, being of such construction as to allow the current to pass freely therethrough. Connecting the other terminal of the magnets 17 and the contact 27 is an additional wire 33. Thus it will be evident that when one of the weighted arms above described is presented against the contact 27, the current will flow from the battery 30 to the ear 20^a, thence through the active arm to the contact 27, from which it follows the wire 33 to the magnets 17 energizing the same, and returning to the battery through the wire 31. It is to be understood that the wiring just described is merely illustrated for the purpose of disclosing an operative construction and need not be followed too closely.

In the drawings, certain specific details of construction have been shown for accomplishing probably the best results, and in the preceding, such details have been described, but it will be evident that I need

not be limited thereto, otherwise than to the extent to which the appended claims restrict me.

I claim:

1. In combination, a shaft shifting member having therein an opening, a power cut-out shaft shiftable longitudinally through said opening to control the power, a spring bearing against the aforesaid member, a catch normally holding said member retracted against the tension of said spring, means to release the catch, and a stop on the shaft into contact with which the aforesaid shaft shifting member is projected when released, whereby to mechanically shift the shaft.

2. In combination, a power driven shaft, a speed arresting brake therefor, a shaft shifting member having therein an opening, a power cut-out shaft slideable freely through said opening, a spring bearing against the aforesaid member, a catch retaining said member retracted against the tension of the spring, releasing means for said catch, a stop on the power cut-out shaft against which the shaft shifting member is projected when released, whereby to mechanically shift said power cut-out shaft to discontinue rotation of the driven shaft under power, and a brake applying arm projecting laterally from the shaft shifting member and having connection with the aforesaid brake, whereby to apply the latter upon projection of said member, and to therefore arrest rotation of said driven shaft.

3. In combination, a power driven shaft, a speed arresting brake therefor, a shaft shifting member having therein an opening, a power cut-out shaft slideable freely through said opening, a spring bearing against the aforesaid member, a catch retaining said member retracted against the tension of the spring, releasing means for said catch, a stop on the power cut-out shaft against which the shaft shifting member is projected when released, whereby to mechanically shift said power cut-out shaft to discontinue rotation of the driven shaft under power, a brake applying arm projecting laterally from the shaft shifting member to the power driven shaft and having connection with the brake whereby to apply the latter upon projection of said member and to thereby arrest rotation of said driven shaft, and a guide on said arm slideable on said power driven shaft.

In testimony whereof I have hereunto set my hand in presence of two subscribing witnesses.
